UNITED STATES PATENT OFFICE.

ECKLEY B. COXE AND SAMUEL SALMON, OF DRIFTON, PENNSYLVANIA; SAID SALMON ASSIGNOR TO SAID COXE.

MECHANICAL MOVEMENT.

SPECIFICATION forming part of Letters Patent No. 369,233, dated August 30, 1887.

Application filed April 25, 1887. Serial No. 236,012. (No model.)

To all whom it may concern:

Be it known that we, ECKLEY B. COXE and SAMUEL SALMON, of Drifton, in the county of Luzerne, and in the State of Pennsylvania, have invented certain new and useful Improvements in Mechanical Movements; and we do hereby declare that the following is a full, clear, and exact description thereof, reference being had to the accompanying drawings, in which—

10 Figure 1 is a perspective view of a plate which is supported by and horizontally movable upon our improved bearings. Fig. 2 is an enlarged perspective view of the roller and one of the bearings which are preferably employed, said parts being separated from each other. Fig. 3 is a side elevation of the same, with its bearings in section; and Figs. 4 and 5 are like views of modifications of said parts.

Letters of like name and kind refer to like 20 parts in each of the figures.

In the use of screening apparatus and in various kinds of mechanism it is desirable that a horizontal gyratory motion should be produced, and for such purpose the part to be 25 gyrated has heretofore been suspended by chains or upon pivoted bars; but in each instance the result has been that the part gyrated had more or less vertical motion and that a considerable amount of friction and wear was 30 caused to the bearing or suspensory parts. To obviate these objections is the design of our invention, which invention consists, principally, as an improvement in mechanical movements, in two relatively movable parts which have 35 parallel inner faces, in combination with a double cone that is placed between and has rolling contact with the inner faces of said parts, and is adapted to furnish a rolling gyrating bearing and support for the upper 40 part, substantially as and for the purpose hereinafter specified.

It consists, further, as an improvement in mechanical movements, in two relatively movable parts which upon or within their parallel 45 inner faces are each provided with a circular track or bearing, in combination with a double cone that is placed between and has rolling contact with said tracks, and is adapted to furnish a rolling gyrating bearing for the 50 upper part, substantially as and for the purpose hereinafter shown.

It consists, further, as an improvement in mechanical movements, in two relatively movable parts which have parallel inner faces, and are each provided within or upon its inner 55 face with a circular guide track or bearing, in combination with a double cone that is placed between and has rolling contact with each of said faces and guide-tracks, and is adapted to furnish a rolling gyrating bearing for the 60 upper part, substantially as and for the purpose hereinafter set forth.

It consists, further, as a means for enabling a relatively gyratory motion to be produced between two parts which have parallel inner 65 faces, and in combination therewith, a double cone that is placed between and has rolling contact with said faces, substantially as and for the purpose hereinafter shown and described.

It consists, further, as a means for supporting a part parallel with and enabling the same to be gyrated over a relatively stationary part, in the combination therewith of two or more double cones which are placed between and 75 have rolling contact with the contiguous parallel faces of said parts, substantially as and for the purpose hereinafter specified.

It consists, further, as a means for supporting a part parallel with and gyrating the same over a relatively stationary part, in the combination therewith of two or more double cones that are placed between and have rolling contact with the contiguous parallel faces of said parts, and a crank which engages with said 85 relatively movable part and operates to move the same bodily in a circular plane, substantially as and for the purpose hereinafter shown.

It consists, further, as a means for supporting a part parallel with and enabling the same 90 to be gyrated over a relatively stationary part without change of circumferential position, in the combination therewith of two or more double cones that are placed between the contiguous parallel faces of said parts and have rolling 95 contact with parallel circular guide-tracks which are provided upon or within each of said faces, substantially as and for the purpose hereinafter set forth.

It consists, finally, as a means for supporting a part parallel with and gyrating the same over a relatively stationary part without

change of circumferential position, in the combination therewith of two or more double cones that are placed between and have rolling contact with parallel circular guide-tracks which 5 are provided upon or within the contiguous parallel faces of said parts, and a crank that engages with said relatively movable part and operates to move the same bodily in a circular plane, substantially as and for the purpose 10 hereinafter shown and described.

As the special organization to which our invention is applied forms no part of such invention, it will be sufficient to illustrate its operation in connection with a supporting-table that is adapted to receive any desired machine, which table consists of a rectangular plate, A, that has any required thickness and corresponds in general size and proportions to the like features of a second plate, B, which is 15 supported in a horizontal position and is 20 usually fixed in place.

Near each corner upon the upper face of the base-plate B is secured a circular plate, C, which at a point midway between its center 25 and periphery is provided with an annular flange, c, that extends upward and in cross-section has the form of an inverted letter V, with the point preferably cut away, so as to produce at such point a horizontal bearing.

Upon the plate C is placed a double cone, D, which within each of its conical faces d is provided with a circumferential groove, d', that transversely corresponds to the shape and size of the flange c, so that when said cone is 30 placed upon the circular plate C its point will coincide with the axis of the latter and its face will rest upon the face of said plate upon each side of said flange, and its said groove will fit over said flange with the sides of said 35 parts in contact, as shown in Fig. 3. If, now, said cone is rotated, it will roll around said flanged plate without change thereon of radial position, and its entire bearing-surface will have contact with the corresponding surface 40 of said plate without slipping and with no friction other than such as is produced by the rolling together of two surfaces.

The plate or table A is provided with four of the circular flanged plates C and C, which 45 are attached to the lower face of said table in positions that correspond to the positions of the like plates upon the base B and rest upon and engage with the upper portions of the cone-rollers D, their bearings upon the faces of 50 said rollers being precisely the same as in case of the lower portions of said cones and their plates. As thus arranged, the entire weight of the table is supported by the cone-rollers, and said table may be gyrated horizontally in 55 either direction by applying sufficient power to overcome its inertia and cause said cones to roll around their lower tracks. As the axis of each cone is oblique to the plane of its track, it will be seen that when traveling around 60 said track the central portion of said cone 65 will describe a circle the diameter of which will determine the amount of movement of

said table in opposite directions. As the contact of said cones with both series of bearing-plates is a rolling contact, the friction caused 70 by their movements is so slight as to render necessary for the movement of the table the expenditure of no appreciable amount of power over what would be required to effect such movement were said table suspended by 75 the theoretically frictionless spring of a clock-pendulum. By the employment of cones and bearing-plates having hardened surfaces the wear upon the same will become practically nothing, and the durability of the mechanism— 80 if breakage is prevented—will exceed that of any possible construction in which there is sliding contact between the bearing-surfaces.

The movement of the table A is preferably secured by means of a crank, E, which has its 85 shaft journaled at or near the center of the base B, and has its upper end or pin, e, journaled within the center of said table. The throw of the crank coincides with the oscillations of the cone-rollers D and D, so that said 90 crank is subjected to no strain other than such as is necessary in order to start said table and keep it in motion. Any desired means may be employed for rotating said crank-shaft; but a belt and pulley are preferably used. 95

The annular flanges c of the plates C operate to prevent radial displacement of the cone-rollers and are preferably employed; but such result can be attained by other forms, if desired. In Fig. 4 is shown a modification in 100 the construction of said parts, in which the roller has plane conical faces d and d and a cylindrical periphery, d', while the bearing-plate has a plane face surrounded by an annular flange, c', that has a face, c'', which inclines upward and outward at the precise angle necessary to enable it to receive rolling contact from the periphery d' of said roller. 105

In Fig. 5 is seen another modification, in which the faces d and d of the roller are plane, and at the end or apex of each is provided a small cylindrical boss, d', that is in a line axially with the axis of said roller and terminates in a cone, d'', as shown. The bearing-plate C has a plane upper face, and at its center is 110 provided with a cylindrical recess, c'', which is in a line axially with the axis of said plate, and has such size as to enable it to receive the boss d' and enable the conical end d'' of the same to bear against and have rolling contact 115 with its sides, as shown.

Having thus thus described our invention, what we claim is—

1. As an improvement in mechanical movements, two relatively movable parts which 120 have parallel inner faces, in combination with a double cone that is placed between and has rolling contact with the inner faces of said parts, and is adapted to furnish a rolling gyrating bearing and support for the upper 125 part, substantially as and for the purpose specified.

2. As an improvement in mechanical movements, two relatively movable parts which 130

upon or within their parallel inner faces are each provided with a circular track or bearing, in combination with a double cone that is placed between and has rolling contact with 5 said tracks, and is adapted to furnish a rolling gyrating bearing for the upper part, substantially as and for the purpose shown.

3. As an improvement in mechanical movements, two relatively movable parts which 10 have parallel inner faces and are each provided within or upon its inner face with a circular guide track or bearing, in combination with a double cone that is placed between and has rolling contact with each of said faces and 15 guide-tracks, and is adapted to furnish a rolling gyrating bearing for the upper part, substantially as and for the purpose set forth.

4. As a means for enabling a relatively 20 gyratory motion to be produced between two parts which have parallel inner faces, and in combination therewith, a double cone that is placed between and has rolling contact with 25 said faces, substantially as and for the purpose shown and described.

25 5. As a means for supporting a part parallel with and enabling the same to be gyrated over a relatively stationary part, the combination therewith of two or more double cones which are placed between and have rolling 30 contact with the contiguous parallel faces of 35 said parts, substantially as and for the purpose specified.

6. As a means for supporting a part parallel with and gyrating the same over a relatively stationary part, the combination therewith of two or more double cones that are placed between and have rolling contact with

the contiguous parallel faces of said parts, and a crank which engages with said relatively movable part and operates to move the same 40 bodily in a circular plane, substantially as and for the purpose shown.

7. As a means for supporting a part parallel with and enabling the same to be gyrated over a relatively stationary part without 45 change of circumferential position, the combination therewith of two or more double cones that are placed between the contiguous parallel faces of said parts and have rolling contact with parallel circular guide-tracks which are 50 provided upon or within each of said faces, substantially as and for the purpose set forth.

8. As a means for supporting a part parallel with and gyrating the same over a relatively stationary part without change of circumferential position, the combination therewith of two or more double cones that are placed between and have rolling contact with parallel circular guide-tracks which are provided upon or within the contiguous parallel 60 faces of said parts, and a crank that engages with said relatively movable part and operates to move the same bodily in a circular plane, substantially as and for the purpose shown and described.

In testimony that we claim the foregoing we have hereunto set our hands this 7th day of April, 1887.

ECKLEY B. COXE.
SAMUEL SALMON.
